DRAFT GEAR

Filed Feb. 10, 1888

2 Sheet-Sheet 2

Inventor:

Harry Barnard

By William G. Ladd 76675.

UNITED STATES PATENT OFFICE.

HARRY BARNARD, OF CHICAGO, ILLINOIS, ASSIGNOR TO UNION DRAFT GEAR CO., A CORPORATION OF ILLINOIS.

DRAFT GEAR.

Application filed February 10, 1922. Serial No. 535,462.

To all whom it may concern:

Be it known that I, HARRY BARNARD, a citizen of the United States, and resident of Chicago, county of Cook, and State of Illinois, have invented certain new and useful Improvements in Draft Gear, of which the following is a specification, and which are illustrated in the accompanying drawings, forming a part thereof.

10 The invention relates to draft gear for railway cars, its object being to provide a simple form of friction draft gear which will develop great power and be smooth in its action.

15 In the embodiment of the invention illustrated in the drawings, there is shown in—

Fig. 1 a detail plan view of the underframing of a car with the improved gear applied thereto, and shown in release position;

Fig. 2, a sectional view of the gear taken on the line 2—2 of Fig. 1;

Fig. 3, a horizontal section taken on the line 3—3 of Fig. 2, but showing the gear in compressed position under buff;

Fig. 4, a perspective of one of the friction plates used in the gear; and

Fig. 5, one of its friction wedge blocks.

There is represented at 10, 10, a pair of 30 draft sills of a railway car which may be of any preferred form of construction, at 11, 11, a pair of draft lugs, and at 12, 12, a pair of buffing lugs attached to the sills. The butt of a coupler is shown at 13, and a 35 conventional form of yoke for inclosing the draft gear, and being attached to the coupler butt, is represented at 14, 14.

The improved draft gear comprises a box-like casing 15, the rear closed end of 40 which is adapted to abut against the buffing lugs 12, 12. A front follower 16 is located forward of the open end of the casing 15, and co-operates with the draft lugs 11, 11, and receives the impact, in buffing, of the 45 coupler butt 13. The length of the casing 15 is such as to provide for the necessary range of movements of the two parts referred to, and preferably to serve as a limiting stop to prevent over compression. A 50 plate 17 is disposed on the median line of the casing 15, and is shown as cast integral with the follower 16, although any form of physical connection between these two parts will serve. The width of the plate is substantially that of the chamber of the casing 55

15, sufficient clearance being allowed for freedom of movement, and the length of the plate may be the same as that of the casing 15. When so proportioned it will serve as an additional limiting stop by making contact with the end wall of the casing.

A pair of friction plates 18, 19, are disposed one at either side of the plate 17, and are preferably of equal width therewith. These friction plates are held against longitudinal movement by means of a key 20 setting through the side walls of the casing 15 and passing through an elongated aperture in the plate 17. The plates 17, 18, and 60 19 collectively divide the chamber of the casing 15 into two compartments, and within each of these compartments is housed 65 friction developing wedge members and cushioning springs. The two sets of these devices being identical in form, but one of 70 them need be described in detail.

Each set of friction developing devices comprises a pair of wedge blocks 21, 22. Each of these blocks is provided with a flat face, the flat faces of the outer blocks 80 engaging the walls of the casing 15 and the flat faces of the inner blocks engaging the plates 18 and 19. The inner faces of the blocks 21 and 22 are inclined, as shown at 24, 25, to form wedging surfaces, and each 85 of the blocks is provided with an elongated aperture 26 to accommodate the key 20 and allow relative movement with reference thereto.

Interposed between the adjacent wedging 90 faces 24 of the blocks 21, 22, there is a triangular block 27, and interposed between the faces 25 of these blocks is a similar triangular block 28. A helical spring 29 reacts between the block 27 and the follower 95 16, and a similar spring 30 reacts between the block 28 and the end wall of the casing 15. Suitable spring guides are formed on the parts between which the several springs react, and these guides, as 31, associated 100 with the follower 16 are of sufficient length to make contact with the guide 32 formed on the triangular wedge-block 27 before the gear is completely compressed, thereby positively moving the block 27 and insuring the 105 advance of the blocks 21 and 22 in buffing.

The various parts of the gear assume the position shown in Figs. 1 and 2 when at rest. Upon the application of buffing stresses the follower 16 is moved backward 110

ly, compressing the springs 29 seated against it, which in turn urge backwardly the triangular wedge-blocks 27, the advance of these blocks spreading apart the blocks 21, 22, and forcing them into frictional engagement with the plates 18, 19, and the latter into frictional engagement with the plate 17.

The blocks 21 and 22 are moved backwardly as well as laterally, and consequently 10 ride up upon the faces of the triangular block 28, with which they make contact, and push these blocks backwardly against the resistance of the springs 30. When the backward movement of the follower 16 has been 15 sufficient to bring the guide stem 31 into contact with the guide stem 32, the springs 29 are no further compressed but the blocks 27 are positively moved backwardly, causing a further compression of the springs 30. As 20 shown, the noses of the triangular blocks 27, 28, are slotted to provide clearance for the key 20.

The springs employed in the gear are of sufficient power to insure a wedging action 25 by the relative approach of the triangular blocks 27, 28, and friction is developed between the parts having a sliding engagement in proportion to the extent of movement of the follower 16.

30 When the pressure of the coupler butt on the follower 16 is relieved the various parts return to the position of rest under the influence of the springs 29, supplemented by the tendency of the wedging elements to separate under the influence of lateral pressure to which they have been subjected. The pitch of the wedging faces is such as to provide for a gradual development of wedging pressure and to facilitate the release action. 35 Upon the release the springs at opposite ends of the gear measurably counteract each other. The tendency of the forward springs is to violently return the follower 16 to normal position. This tendency is not only resisted by the frictional engagement of the various parts, but the too sudden release of 40 this engagement is insured by the expansive action of the rearward springs.

Upon the application of draft stresses the 50 action of the gear is the same as in buffing, except that the casing and its contained elements other than the plate 17 move forwardly.

Various changes of detail may be made 55 within the scope of the invention, as, for example, the rear end of the casing, while shown as attached to the body, need not necessarily be so.

I claim as my invention—

60 1. In a draft gear, in combination, a casing having a closed end, a friction plate movable on the longitudinal median plane of the casing, a pair of plates frictionally engageable with the opposite faces of the

65 active longitudinal movement of the pair of plates and the casing, and means including springs at each end of said casing for pressing the pair of plates against the central plate.

70 2. In a draft gear, in combination, a casing, resilient means associated with said casing, a friction plate movable on the longitudinal median plane of the casing, a pair of plates frictionally engageable with the opposite faces of the first-named plate, means for preventing relative longitudinal movement of the pair of plates and the casing, and wedge means operated by the initial movement of said resilient means for pressing the pair of plates against the central plate.

75 3. In a draft gear, in combination, a casing, a follower therefor, a friction plate rigidly secured to said follower and movable on the longitudinal median plane of the casing, a pair of plates frictionally engageable with the opposite faces of the first-named plate, means for preventing relative longitudinal movement of the pair of plates and the casing, means for pressing the pair of plates against the central plate, and spring means for withdrawing the central plate after an advance movement.

80 4. In a draft gear, in combination, a casing having a closed end, a follower opposed to the open end of the casing, a longitudinally movable plate centrally disposed in the casing and normally projecting beyond its open end, a pair of plates flanking and frictionally engaging the first-named plate and being anchored to the casing against longitudinal movement, two pairs of friction shoes one of each pair being seated against the side walls of the casing and the other 85 against one of the pair of plates, the adjacent faces of each pair of shoes being wedge-shaped, a wedge block interposed between opposed wedge faces of the shoes, and springs reacting between the several wedge blocks and the end of the casing and the follower, respectively.

90 5. In a draft gear, in combination, a casing having a closed end, a follower opposed to the open end of the casing, a longitudinally movable plate centrally disposed in the casing and normally projecting beyond its open end, a pair of plates flanking and frictionally engaging the first-named plate and being anchored to the casing against longitudinal movement, two pairs of friction shoes one of each pair being seated against the side walls of the casing and the other 95 against one of the pair of plates, the adjacent faces of each pair of shoes being wedge-shaped, a wedge block interposed between opposed wedge faces of the shoes, springs reacting between the several wedge blocks 100 and the end of the casing and the follower, respectively, and spring guides carried by 105

the follower and engageable with a pair of the wedge blocks upon the compression of the springs.

6. In a draft gear, the combination of a casing having a closed end, a friction plate moving in the longitudinal median plane of the casing, a pair of friction plates engaged with the opposite faces of the first named plate and extending substantially from one end of said casing to the other, means for preventing relative longitudinal movement of the pair of plates and the casing and spring pressed wedged means for pressing the pair of plates against the first named plate.

7. In a draft gear, the combination of a casing, a follower, a plate centrally disposed in the casing and secured to the follower, friction plates flanking and frictionally engaged with the first named plate and anchored against longitudinal movement in the casing, wedge means between the friction plates and the casing, springs between the follower and the wedge means and means at the end of said casing opposite said follower for yieldingly resisting relative movement of said wedge means in one direction relatively to said casing.

8. In a draft gear, the combination of a casing having a closed end, a follower opposed to the open end of the casing, a plate centrally disposed in the casing and secured to the follower, friction plates flanking and frictionally engaged with the first named plate and anchored against longitudinal movement in the casing, relatively movable wedge elements between each friction plate and the casing and springs between said wedge elements and the closed end of the casing, and between said elements and the follower.

9. In a draft gear, the combination with a casing, a follower, a plate carried by said follower and operating within said casing; a pair of friction plates engaging opposite faces of the first named plate, springs, means engaged by said springs for forcing the pair of plates against the first named plate, and means carried by the follower for positively engaging said spring pressed means during the final relative movement of said plates for further increasing the pressure between said pair of plates and said first named plate.

HARRY BARNARD.
